UNITED STATES PATENT OFFICE.

ROSCOE BEAN, OF BEREAL, OHIO, ASSIGNOR TO LIBERTY METAL PRODUCTS COMPANY,
OF BEREAL, OHIO, A CORPORATION OF IOWA.

VALVE-REFACER.

1,330,778.

Specification of Letters Patent. Patented Feb. 17, 1920.

Application filed January 28, 1916. Serial No. 74,830.

To all whom it may concern:

Be it known that I, Roscoe BEAN, a citizen of the United States, residing at Berea, in the county of Cuyahoga and State of 5 Ohio, have invented certain new and useful Improvements in Valve-Refacers, of which the following is a specification, reference being had therein to the accompanying drawing.

- 10 The invention relates to valve refacers and the like and is in the nature of a further development and improvement of the device shown and described in my co-pending application, Ser. No. 36,640, filed June 28, 1915. 15 Owing to the high temperature at which valves operate in some gas engines the surfaces of the same may harden and have deposited upon them carbon which causes great inconvenience. The usual cutting tool will 20 not stand up to the work under such conditions. The valve must, therefore, be ground by some abrasive material before being refaced by the cutting tool.

It is an object of this invention to provide 25 a tool which will perform either the abrading or cutting, or both, of the valve face. It is a further object of the invention to provide adjustable and detachable means for the tool to support the valve and stem for 30 finishing, whereby said means can be adapted to reductions in size of the stem due to the wear, thereby insuring a perfect alignment of the valve stem. Another object of the invention is to provide certain detail 35 improvements in the cutting tool.

In the accompanying drawings, Figure 1 is a vertical, sectional view of the tool showing the valve in position on the abrading end thereof; Fig. 2 is a vertical sectional view 40 taken at right angles to the section shown in Fig. 1 and inverted; and Fig. 3 is a plan view of the tool looking down on Fig. 2.

In the embodiment of the invention here shown the tool comprises a frame member 1 45 with an abrading device or disk 2 located at one end and a cutting device or disk 3 located at the other end. These disks 2 and 3 are mounted upon rings 4 and 5, respectively, located at the ends of the frame member 1. The frame member comprises a pair of members 6 and 7 connecting the two rings. Transverse connecting pieces 8 and 9 are located between the members 6 and 7. These connecting pieces 8 and 9 project beyond the 55 members 6 and 7, as indicated at 8' and 9',

forming lugs between which the tool can be mounted in a vise when in use. The frame member comprising the rings 4 and 5, the members 6 and 7 and the connecting pieces 8 and 9, are integral and cast in one piece. 60 It will be understood, however, that other constructions may be used. The transverse connecting pieces 8 and 9 have vertically extending apertures therein, as indicated at 10. These apertures are tapered and screw-threaded. A bushing 11 with an aperture 12 therein is located within each aperture 10. Each bushing comprises a tapered screw-threaded portion 13 with longitudinal slits or apertures 14 therein and a head 15. By 70 this construction it will be seen that bushings having apertures of different sizes may be located within the apertures 10 and furthermore that the said bushings can be adjusted to increase and decrease the size of 75 the aperture in each bushing, this adjustment being performed by means of a wrench or by the hand through the head 15. The abrading disk 2 consists of substantially a frusto-conical shell having an opening 16 at 80 its smaller end. The inner surface of this conical shell is adapted to be used as an abrasive medium, as indicated at 17. The large end of the shell has a horizontal circumferential flange thereon, indicated at 18, 85 which is adapted to be detachably secured to the ring 5 by means of screws 19. The cutting disk 3 consists of substantially a frusto-conical shell having an opening 20 at 90 its reduced end and a circumferential flange 21 located at its enlarged end. This flange 21 is detachably secured to the ring 5 by means of screws 22.

The cutting disk 3 is made from sheet metal of sufficiently heavy gage to give the 95 necessary rigidity and strength thereto and is preferably formed by the use of dies, although it will be obvious that it could be formed by hand. The frusto-conical shell of the cutting disk is preferably struck from 100 a flat sheet of metal. This cutting disk has portions 23 struck therefrom extending inwardly above the inner surface of the shell. These portions 23 are arranged circumferentially on the inside of the frusto-conical shell 3, forming the cutters for the tool, and obliquely to the path of rotation of the valve face, thereby insuring a drawing cut which renders the same very efficient as to speed, ease of operation and smoothness of finish, 110

The struck up portions 23 are formed by making a longitudinal slit 24 and two slits 25 and 26 at right angles to and at the ends of the slit 24 and bending the cut portion up. 5 The struck up portion thus made it is evident will then comprise side edges 27 and 28 and a longitudinal edge 29, this edge constituting the cutting edge. As here shown, each struck up portion is substantially rectangular in configuration and the cutting edge is spaced some distance from the main portion of the frusto-conical shell. As stated above, the portions 23 are arranged obliquely to the path of rotation of the valve 10 face or of the tool as it is immaterial which is rotated. As will be seen from an inspection of Fig. 3 this obliqueness is such that when the plane of any struck-up portion is prolonged it will intersect the plane of a 15 next succeeding struck-up portion, the line of intersection being located substantially on the sheet metal frusto-conical shell. A sample valve is indicated at 30 in Fig. 1, the valve face having any specified angle of inclination. The face is also conical in configuration. Inasmuch as each cutting edge 25 is located obliquely to the valve face and has a substantial width transversely it must be shaped to fit the curve of the said valve 30 face, whereby the cutting edge both transversely and longitudinally thereof will squarely and completely engage the valve face. To obtain these results each edge, as shown, has a diagonal scoop therein where- 35 by the corners 31 and 32 are higher than the corners 33 and 34. This scoop gives the cutting edge 29 a more or less longitudinal curve and a more or less transverse curve. The particular structure of the edge, as 40 shown in the drawing, is more or less distorted to clearly bring out the point. The idea is to so shape the edge that it will squarely engage the valve face at all points across the same, whereby the valve face will 45 be cut smoothly and evenly and the cutting edge will engage the same firmly. It is to be understood, however, that these struck-up portions can be modified as to their shape, size and arrangement, whereby they may be 50 adapted to valves having faces of different angles and to valves of different sizes. When the tool is to be used it is clamped within a vise with the abrasing surface 2 at the upper end thereof. The valve, as shown at 30, 55 is then placed within the shell 2 with its stem extending through the opening 16 and through the apertures 12 of the bushings. The valve is then rotated until the rough projections caused by either usage or by car- 60 bon have been removed. The tool is then reversed with the cutting surface up, as shown in Fig. 2. The valve 30 is then placed within the conical shell 3 with its stem projecting through the opening 20 and through the 65 apertures in the bushings 11. The valve is

then rotated and finished. The valve stem is placed in proper alinement with the cutting tool by adjusting the bushings to make the fit between the apertures 12 thereof and the valve stem more or less close. In case 70 the apertures within the bushings are not sufficiently large or are too large, the bushings in use can be replaced by others of different sizes.

In connection with the above operations it 75 will be understood that it will not be necessary in all cases to go through the abrasing operation and the tool can also be made without the abrasing part. It is contemplated to provide bushings of different sizes 80 with each tool in order that the correct bushing can be placed within the tool when necessary. It will, therefore, be seen that I have provided a tool which is simple in construction and is adapted for a wide range of uses 85 with valves of different sizes and with stems of different sizes. It will also be apparent that the finishing of the valve face by means of the above-described tool will be more complete and even. The tool is furthermore 90 very easily operated and the valve can be easily and quickly refaced.

It is to be understood that the invention embodying the frusto-conical shell with the struck-up portions is not to be limited to 95 valve refacers as it is contemplated, for instance, to use the invention in connection with valve seat refacers.

While I have shown and described one embodiment of my invention it will be understood that this has been chosen for the purposes of illustration only and that I do not desire to be limited to the details of construction shown and described, for obvious modifications will occur to a person skilled 100 in the art.

Having thus fully described my invention, what I claim as new and desire to secure by Letters Patent, is:—

1. In a valve refacer, a frame, an abrasing 110 device and a cutting device mounted on said frame in spaced apart relation, and a bushing mounted on said frame between said devices.

2. In a valve refacer, a frame comprising 115 spaced apart rings connected by intermediate portions, a shell comprising an abrasing surface mounted on one ring and a shell comprising a cutting surface mounted on the other.

3. In a valve refacer, a frame, a frusto-conical abrasing device mounted on said frame, a frusto-conical cutting device mounted on said frame, the smaller portions of said devices having openings therein, and 120 a bushing located between said devices and alined with said openings.

4. In a valve refacer, a frame, said frame having a tapered screw-threaded aperture 130 therein, a frusto-conical cutting device

mounted on said frame, the reduced portion of said device having an opening therethrough and a bushing having means thereon to coöperate with said tapered screw-threaded aperture and located below to one side of said opening.

5. In a valve refacer, a frame comprising spaced apart rings, means for connecting said rings and a transverse connecting piece

having an aperture, an abrasing device connected to one of said rings and a cutting device connected to the other of said rings, said devices having openings at their adjacent ends, and an adjustable bushing mounted in said aperture between said devices.

In testimony whereof I affix my signature.

ROSCOE BEAN.
